US00D824656S

(12) United States Design Patent (10) Patent No.: US D824,656 S
Gavrieli et al. (45) Date of Patent:  *Aug. 7, 2018

(54) YELLOW SOLE AND HEEL STRIPE FOR A SINGLE-SOLE SHOE	1,214,666 A	2/1917	Ford
	1,519,009 A	12/1924	Reina
	1,525,848 A *	2/1925	Bonaventure A43B 5/12 36/113
(71) Applicant: Gavrieli Brands, LLC , Beverly Hills, CA (US)	1,587,377 A	6/1926	Grosjean
	1,650,466 A	11/1927	Righter
	2,224,590 A	12/1940	Boivin
	2,268,777 A	1/1942	Scholl
(72) Inventors: Kfir Gavrieli , Los Angeles, CA (US); Dikla Gavrieli , Los Angeles, CA (US)	D133,819 S *	9/1942	Harris D2/939
	D135,791 S	6/1943	Beebe
	2,323,563 A	7/1943	Nugent
(73) Assignee: Gavrieli Brands LLC , Beverly Hills, CA (US)	2,342,882 A	2/1944	Meltzer
	D141,871 S	7/1945	Braun
	2,383,585 A	8/1945	Bindner
(*) Notice: This patent is subject to a terminal disclaimer.	D149,685 S *	5/1948	Sandler D2/935
	D150,729 S *	8/1948	Sandler D2/923
	D166,090 S *	3/1952	Maling D2/897
() Term: 15 Years	2,772,488 A	12/1956	Meltzer
(21) Appl. No.: 29/570,760	2,904,814 A	9/1959	Scholl
(22) Filed: Jul. 12, 2016	3,148,378 A	9/1964	Tibbitts
	D200,897 S *	4/1965	Mitchell D2/919
	D220,464 S	4/1971	Hayoshi
	D247,396 S *	3/1978	Schlerth D2/939
	4,412,393 A	11/1983	Terlizzi, Jr. et al.
	D275,525 S	9/1984	Nakao
	4,674,206 A	6/1987	Lyden
	D295,692 S *	5/1988	Zuidema D2/950
	D300,085 S	3/1989	Ito et al.
	RE33,018 E	8/1989	Ostrander
	4,899,412 A	2/1990	Ganon
	D316,773 S	5/1991	Valle
	5,012,541 A	5/1991	Ganon
	D339,669 S *	9/1993	Miller D2/919
	5,282,326 A	2/1994	Schroer, Jr. et al.
	5,241,050 A	6/1995	Laganas
	5,699,629 A	12/1997	Munsch

CLAIM

The ornamental design for a yellow sole and heel stripe for a single-sole shoe, as shown and described.

DESCRIPTION

The file of this patent contains at least one drawing executed in color. Copies of this patent with color drawing(s) will be provided by the Office upon request and payment of the necessary fee.

FIG. 1 is a perspective view of a yellow sole and heel stripe for a single-sole shoe shaded to show the color Yellow, showing our new design;

FIG. 2 is a first side view thereof;

FIG. 3 is a second side view thereof;

FIG. 4 is a top view thereof;

FIG. 5 is a bottom view thereof;

FIG. 6 is a front view thereof;

FIG. 7 is a back view thereof;

FIG. 8 is a perspective view of another embodiment of our new design of a yellow sole and heel stripe for single-sole shoe of FIG. 1, illustrated in conjunction with a disclaimed shoe upper, where the yellow portions are indicated using the USPTO convention of vertical and horizontal cross-hatched lines for yellow or gold;

FIG. 9 is a first side view thereof;

FIG. 10 is a second side view thereof;

FIG. 11 is a top view thereof;

FIG. 12 is a bottom view thereof;

FIG. 13 is a front view thereof; and,

FIG. 14 is a back view thereof.

The broken lines showing elements in the above described Figures are for illustrative purposes only and form no part of the claimed design.
